UNITED STATES PATENT OFFICE.

FREDERICK J. PULLIS, OF JERSEY CITY, NEW JERSEY.

MAIL-BAG EJECTOR FOR TOY RAILWAYS.

Application filed April 9, 1926. Serial No. 100,938.

This invention relates to toy railways and has particular reference to a mail bag ejecting attachment therefor.

Heretofore toy railways have been provided with mail bag catchers for the purpose of catching toy mail bags from stationary bag-supporting elements alongside of the track, but no means has heretofore been devised to work in connection therewith for ejecting the mail bag, and, hence, after a certain number have been caught, the toy must be stopped and the bags either fished out with a wire or otherwise removed.

The present invention comprehends in combination with a toy railway equipped with a mail bag catching device, a means for automatically ejecting the bags subsequent to the catching operation, which eliminates the necessity of stopping the train for this purpose, thereby adding to the attractiveness of the toy and rendering the same more amusing.

The invention furthermore comprehends a mail bag ejecting device for toy railways, which is comparatively simple in its construction, inexpensive to produce, and readily applicable to or detachable from the railway.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a side view of a toy railway illustrating the same equipped with a mail bag ejecting device constructed in accordance with the invention;

Fig. 2 is a plan view thereof;

Fig. 3 is an enlarged transverse sectional view;

Fig. 4 is a plan view of the train carried element of the ejector removed from the train;

Fig. 5 is a detail side view illustrating the detachable trip clip.

Referring to the drawings by characters of reference, A designates a toy mail car having doorways B, and mounted on wheels

for movement over the rail C of a track. Heretofore toy railways have been equipped with a mail bag supporting device D suitably connected with and disposed alongside the track rails, and the mail car A has been provided with a catching arm E for engaging, removing and throwing the mail bags F through the doorway B into the mail car.

In the present invention the mail bag ejecting device consists of a trough-like member 10 which is pivotally attached at 11 to a base 12, which base is provided with dependent resilient terminal arms 13 designed to frictionally engage the opposite sides of the car A with the base 12 extending transversely of the car at the doorways so as to dispose the trough-like member 10 adjacent the doorway upon which the catching hook E is mounted. The base 12 is formed with an upwardly projecting finger 14 adapted to engage under the floor 15 of the trough-like member for normally supporting the same at a lateral inclination with the lower hinged end adjacent the doorway upon which the catching arm E is mounted. The free uppermost end of the trough-like member 10 is provided with a weight 16 for normally maintaining the member in engagement with the stop finger 14. The floor or bottom wall 15 adjacent the hinged end is offset upwardly at 17 and is provided with an extension 18 projecting outwardly through the doorway B and provided with a vertical depending leg 19 having an outturned horizontal foot 20. The foot 20 has detachably associated therewith a trip clip 21, which consists of a strip of material bent medially of itself into substantially arcuate form to constitute a cam 22, the remaining ends 23-23 being extended inwardly toward each other in overlapping relation and formed with opposite hooked extremities 24 which, due to the inherent resiliency of the material from which the trip clip is constructed, sets up a clamping action of the hooked extremities with the foot 20 to retain the trip clip in place against accidental displacement.

The mail bag ejecting device further includes a ramp 25 similarly constructed to the trip clip and detachably associated in the same manner as the trip clip with the horizontally inwardly projecting arm 26 of the supporting strip 27 disposed alongside of the

track and detachably connected therewith by the base portion 28 which is formed with resilient gripping fingers 29.

In use and operation, the bags F when caught by the arm E from the mail bag supporting device D, are thrown through the doorway B where they are received in the trough-like member 10 and retained in place due to the upwardly offset portion 17 until 10 the train reaches the ejecting ramp 25. At this point the cam portion 22 of the trip clip engages the ramp 25 which effects a downward swinging movement or depression of the leg 19 and a consequent further tilting of the trough-like member 10 to substantially the position illustrated in dotted lines in Fig. 3. The bags will thus be gravitationally ejected from the train, and due to its motion, thrown clear of the ramp 25. 15 20 The weight 16 will effect a return of the trough-like member 10 to its normal position after the trip clip is disengaged from or clear of the ramp 25.

From the foregoing it will be seen that a mail bag ejecting device for use in connection with toy trains equipped with mail bag catchers, has been devised, which eliminates the necessity of stopping the train to remove the bags and it is obvious that the player or user has only to place the bags on the mail bag supporting device D as they are thrown or ejected from the train. In event it is desired to render the ejecting device inactive, either the trip clip or the ramp 30 may be removed by pressing inwardly on the opposite ends thereof to disengage the hooked terminals 24 from the foot 20 or arm 26. It is also obvious that the ejecting device may be readily removed from the car by 35 disengaging the dependent arms 13 upon upward movement of the base 12.

I claim:

1. A mail bag ejecting device for toy rail-
way cars, comprising a trough-like bag
45 receiving member, a base to which the same
is pivotally connected, means for detachably
connecting the base with the car, an exten-
sion on said member projecting through the
door of the car and having a depending leg
50 provided with an outturned horizontal foot,
a trip clip detachably carried by the foot,
a ramp detachably connected with the rail-

way track and disposed alongside thereof
in the path of movement of the trip clip for
engagement thereby to swing the trough-like
55 member to an angular position for gravita-
tionally ejecting a bag.

2. A mail bag ejecting device for toy rail-
way cars, comprising a trough-like bag re-
ceiving member, a base to which the same is
pivotally connected, means for detachably
connecting the base with the car, an extension
60 on said member projecting through the door
of the car and having a depending leg pro-
vided with an outturned horizontal foot, a
trip clip detachably carried by the foot, a
ramp detachably connected with the railway
track and disposed alongside thereof in the
path of movement of the trip clip for eng-
agement thereby to swing the trough-like
65 member to an angular position for gravita-
tionally ejecting a bag, the detachable
trip clip being removable for the purpose
of rendering the ejecting means inoperative,
and consisting of a strip of material having
70 an arcuate cam-shaped portion and a pair of
inwardly projecting ends formed with
hooked extremities normally moved toward
each other by the inherent resiliency of the
material from which the strip is formed to
75 frictionally clamp the foot.

3. In a mail bag ejecting device for toy
railways of the character set forth, a base
strip having downturned extremities adapted
80 to be arranged transversely of a toy car
with the extremities extending through the
doorway and frictionally engaging the op-
posite sides of the lower portion of the car,
a trough-like bag receiving element pivoted
85 to one end of the base strip and disposed
transversely of the car, means on the base
strip for normally holding the trough-like
member projecting through the doorway and
having an upwardly offset portion at its
90 juncture with the member, said extension
having a depending leg and a horizontal
laterally projecting foot, a removable cam-
shaped trip clip carried by the foot, and a
ramp element carried by the railway track
95 and disposed alongside thereof in the path
of movement of the trip clip for tripping the
same to eject the bag gravitationally from
the trough-like member.

FREDERICK J. PULLIS.
